CLAIM

The ornamental design for castle-style climbing equipment display, as shown and described.

DESCRIPTION

FIG. 1 is a left front perspective view of the display design;

FIG. 2 is a front plan view of the display design;

FIG. 3 is a rear plan view of the display design;

FIG. 4 is a left side view of the display design;

FIG. 5 is a right side view of the display design; and,

FIG. 6 is a top plan view of the display design.

An internal supporting frame accepts placement of climbing equipment product (e.g. ladders of various styles) for retail display in a specifically arranged configuration as shown. The display design appearance is fixed by the rigid arrangement required by the frame which accepts specific quantities and types of climbing equipment for display which simulates a castle shape.

FIG. 1

FIG. 2

FIG. 3

FIG. 4

FIG. 5

FIG. 6
